UNITED STATES PATENT OFFICE

ROBERT B. DOPH, OF OAKLAND, CALIFORNIA

DESIGN FOR A SOAP BAR

Application filed March 5, 1929. Serial No. 30,322. Term of patent 14 years.

To all whom it may concern:

Be it known that I, ROBERT B. DOPH, a citizen of the United States, residing at Oakland, in the county of Alameda and State of California have invented a new, original, and ornamental Design for Soap Bars, of which the following is a specification, reference being had to the accompanying drawing, forming part thereof,

The letter being of a color contrasting with the color of the bar of soap.

I claim:

The ornamental design for a soap bar as shown and described.

ROBERT B. DOPH.
